UNITED STATES PATENT OFFICE.

EDMUND GEORGE BAXTER, OF KENSINGTON, LONDON, ENGLAND.

CASEMENT-WINDOW.

1,332,593.

Specification of Letters Patent.

Patented Mar. 2, 1920.

Application filed September 4, 1919. Serial No. 321,642.

To all whom it may concern:

Be it known that I, EDMUND GEORGE BAXTER, of 9 Vicarage Gardens, Campden Hill, Kensington, London, W. 8, England, civil 5 engineer, a subject of the King of Great Britain and Ireland, have invented certain new and useful Improvements in Casement- Windows, of which the following is a specification.

10 This invention relates to casement windows and has for its object to provide an improved form of window of this kind adapted to open at either side alternatively and to be hinged at the other side. In other words 15 the object of my invention is to provide a casement window which is not restricted to being opened at one particular side and hinged at the opposite side but which can be swung open at either one side or the other 20 as may be desired according to, or in consequence of, the wind or other conditions prevailing at that moment.

The invention consists essentially in the improved either way casement window, both 25 sides, that is both stiles, of the opening member of which are provided with one or more hinges, one leaf of each hinge being screwed or otherwise fixed to the stile and the other leaf of the hinge being loose, and in which 30 the loose hinge leaves are detachably secured in engagement with locking devices let into the uprights of the fixed window frame, in such a manner that either stile of the window can be released at will to open 35 the window on that side by releasing the locking connection between the loose leaf on the corresponding stile and the frame.

The preferred construction of my improved either-way casement window will 40 now be described with the aid of the accompanying drawings, in which Figure 1, is a fragmentary front view from the interior of the apartment of the lower part of the improved casement window; Fig. 2 is a sectional view on the line II-II of Fig. 1. Figs. 3 and 4 illustrate details of the said 45 preferred construction; Figs. 5 and 6 are side views of the members of the movable hinge, and Figs. 7 and 8 are plan views 50 thereof.

Referring to the drawings, part of a wooden stile 1 of the opening member of the window is shown in Figs. 1 and 2 in the closed position in engagement with the corresponding wooden upright 2 of the fixed frame of which the other upright is shown 55 at 3 and the lower rail at 4 (Fig. 1).

The outer side of the stile 1 is provided with a hinge of which one leaf 5 is fixed by means of screws or other suitable means 60 (not shown) to a countersunk portion of the said outer side while the other leaf 6 of the hinge is loose and can rotate around a pivot pin 7 connecting the members of the hinge. The fixed hinge 5 is formed as shown in 65 Figs. 5 and 8, having integral therewith a member 5', extending at right angles thereto, and at the outside of the angle between these two members a plurality of cylindrical members 13 are formed, which are adapted 70 to articulate with similar members formed on the loose hinge 6, all of the members being provided with a central opening so that when the members are articulated together the openings are in alinement and adapted 75 to receive the pintle or pivot 7. The loose hinge is formed as shown in Figs. 6 and 7, having integral therewith a portion 6', at right angles thereto, and a similar arrangement of cylindrical portions 13 integral 80 with the portions 6 and 6' at the outside of the angle formed between these two portions. The portion 6 has also formed integral therewith and with the cylindrical portions a block portion 14 on the face of 85 the portion 6 which is adapted to lie contiguous to the member 5, when the hinge members are assembled, the block 14 thus serving to maintain the members 5 and 6 spaced apart. For maintaining the members 5 and 6 in parallel relation, as shown in 90 Fig. 2, even when the window sash is open, I provide a flat spring 8, which may be secured to the stile 1 by means of the screws 9 and 10 which secure the member 5' to the 95 stile, a spacing block 11 being secured in position between the spring 8 and the portion 5' of the fixed member of the hinge. The extreme free end of the spring 8 is tapered and is adapted to rest on the tapered 100 outer side of a pin or plug 12, formed on the uppermost cylindrical member 13 carried by the loose member 6 of the spring. By reason of this construction the spring 8 resists any tendency of the loose member 6 to rotate 105 on the pivot 7, and thereby maintains the portion 14 in contact with the face of the member 5, even when the window is open, while the block 14 prevents the members 5 and 6 from closing any nearer together than 110 as shown in Fig. 2.

The upright 2 of the wooden frame of the window is cut away to form a recess opposite to each hinge on the stile 1 to enable the

hinge leaves 5 and 6 to come into closed position in which they embrace between them a plate 16 preferably of metal secured in the recess 15 by means of screws 17 and 18, for example (Fig. 3).

From the interior of the apartment a hole 19 is bored in the upright 2 of the frame extending to the vicinity of the recess 15 and plate 16 therein and terminating in a hollow space 20, the hole 19 and space 20 accommodating a spindle 21 on the inner end of which is secured a locking tumbler 22 fixed to a square part of the spindle 21 by a screw 23, the tumbler 22 having a projecting nose adapted to engage in a recess 24 milled or otherwise formed in the outer surface of the loose leaf 6 of the hinge on the stile 1. The outer end of the spindle 21 terminating within the apartment is supported in a bearing bushing 25 inwardly projecting from a plate 26 adapted to be secured upon the surface of the upright 2 of the frame, the spindle 21 being held in its correct position within the bushing 25 by means of a screw 27, for example, projecting through the wall of the bushing 25 into a circumferential groove formed in the spindle 21 which is conveniently provided at its projecting end with a squared portion adapted to receive a similarly shaped hole in a handle 28 adapted to rotate the spindle 21 and thus to operate the locking member 22 mounted thereon, the handle being secured in position on the spindle by a screw 30. In order to support the tumbler 22 in its locking position in engagement with the recess 24 in the loose leaf 6 the space 20 may advantageously be fitted with a steel plate 29 against which bears the rear portion of the locking tumbler 22 in its locking position. To retain the handle 28 in its locking position shown in Fig. 2 a locking pin 30 is provided which is passed through a hole 31 in the handle and holes registering therewith in the plate 26 and upright 2 of the frame.

Two or more hinges formed as described above may be provided on each stile of the opening member of the window when this is large enough to require the support of more than one hinge. In this case the handles 28 are each provided with a tail piece 32 and these tail pieces are connected together by vertically arranged connecting bars 33, one on each side of the window, the connection being made by screws 34, for example, as shown in Figs. 1 and 2. In the arrangement illustrated the upper ends of the bars 33 are supposed to be connected to a second handle (not shown) on each side of the window.

In order to interlock the locking means on one side of the window with the locking means on the other side of the same so that both sides of the window cannot be released at the same time, the lower ends of the con-

necting bars 33 rest upon normally horizontal arms 36, 37 respectively of two bell crank levers pivoted on the lower rail 4 of the window frame in such a manner that the arms 36, 37 extend outwardly, that is, to the left and right respectively from the pivots of the bell cranks which are shown at 38 and 39, while between the downwardly depending arms 40 and 41 respectively of the bell cranks a horizontal bar 42 is arranged to slide longitudinally being provided for this purpose with slots 43 and 44 through which pass screws or pins 45 and 46 which are driven into the wooden lower rail 4. The bar 42 is given such a length that if one connecting bar 33, for example that shown on the right of Fig. 1, is depressed by the rotation of the handle 28 into position to unlock the corresponding side of the window the said bar 42 is thereby driven to the left hard against the depending arm 40 of the bell crank on the left the effect being to force the horizontal arm 36 of the said bell crank to tend to raise the lower end of the bar 33 on the left and thus to prevent this side of the window from being released at the same time as the right hand side, as will readily be understood from Fig. 1 of the drawings.

In operation supposing that it is desired to open the right hand side of the window shown in Fig. 1, the locking pin 30 is first withdrawn from the handle 28 which is then moved into the open position shown on the right of Fig. 1 thus rotating the spindle 21 to bring the locking tumbler 22 into the full line position shown in Fig. 3 in which the loose leaf 6 of the hinge on the corresponding stile of the window is released. This stile can now be pushed outward to open the window which swings in the usual manner upon the hinge pin 7 of the hinge on the left hand side, the loose leaf 6 of which is retained locked to the upright 2 of the window frame by the locking tumbler 22 engaging in the recess 24 formed in the back of the said loose leaf 6. In order to open the left hand side of the window the right hand side must first be closed and the corresponding locking handle 28 be turned down into locking position thus lifting the right hand connecting bar 33 upward and permitting the horizontal interlocking bar 42 to be moved to the right, this movement being effected by turning the left hand handle 28 into open position, whereupon the left hand side is released and can be pushed open, the window now swinging upon the hinge pin 7 on the right hand side.

In order to prevent a handle 28 from being turned into closed position while the corresponding side of the window is open thus releasing the interlocking device and enabling the other side also to be opened, I provide an automatic safety catch such as that shown in Fig. 4 consisting of a depend-

ing arm 47 the end of which is formed with a hook 48, and a horizontal arm 49 engaged by a flat spring 50 tending to turn the device on its pivot pin 51 into the position shown in Fig. 4 in which the hook 48 comes beneath the handle 28. The device comes into this position only on the corresponding side of the window being actually opened that is, after the handle 28 on that side has been raised into the open position shown in the right of Fig. 1, in which position therefore the said handle is retained until that side of the window is again closed whereupon a suitable pin or other projection 52 secured upon or near the edge of the stile 1 pushes the horizontal arm 49 to the right as seen in Fig. 4 against the pressure of the spring 50 thus moving the hook 48 to the left away from the handle 28 and thus permitting the latter to be turned down into locking position.

What I claim and desire to secure by Letters Patent is:—

1. In a casement window, the combination with a hinge on each stile of the window sash, one leaf of each hinge being fixed to the stile and the other leaf pivoted to said fixed leaf, and means for flexibly maintaining said leaves in spaced parallel relation, of a two-part locking means carried by the window frame and adapted to engage one of said leaves therebetween for detachably securing the said leaf to the frame.

2. In a casement window, the combination with a hinge on each stile of the window sash, one leaf of each hinge being fixed to the stile and the other leaf pivoted to said fixed leaf, and means for flexibly maintaining said leaves in spaced parallel relation, of a two-part locking means carried by the window frame, one part of said locking means being adapted to enter the space between said leaves and the other part being adapted to exert pressure on one of the leaves thereby to retain it in frictional engagement with said first part whereby the leaves are detachably secured to the frame.

3. In a casement window, the combination with a hinge on each stile of the window sash, one leaf of each hinge being fixed to the stile and the other leaf being loose, of a plate secured to each side of the window frame in line with and edge-on toward the opening between the loose and fixed leaves of the hinge and adapted to be embraced between the said leaves in the closed position of the window, a spindle journaled in the window frame in the vicinity of each plate, a recess on the outer face of the loose leaf of each hinge, a locking tumbler fixed upon the spindle adapted to engage in said re-

cess, a crank handle on the outer end of the spindle, and interlocking means preventing the two handles on opposite sides of the frame from being moved into releasing position at the same time. 65

4. In an either-way casement window, the combination with a number of hinges on each side of the window sash stile, one leaf of each hinge being fixed to the stile and the other leaf being loose, of a corresponding number of locking devices for detachably securing the loose hinge leaves on both stiles to the frame, handles for operating the said devices, a vertically arranged bar 75 connecting the handles on one side of the window enabling all these handles to be operated by one of them, a vertically arranged bar connecting the handles on the other side of the window enabling all these handles to 80 be operated by one of them, a bell crank lever having a normally horizontal arm engaging the lower end of one connecting bar and a normally vertical arm, another bell crank lever having a normally horizontal 85 arm engaging the lower end of the other connecting bar and a normally vertical arm, both bell cranks being pivoted on the frame between the two vertical bars, and a sliding horizontal bar arranged between the ends of 90 the vertical arms of the two bell cranks to prevent both of the sets of handles from being moved into releasing position at the same time.

5. In an either-way casement window, the combination with a hinge on each stile of the window sash, one leaf of each hinge being fixed to the stile and the other leaf being loose, of a part on the window frame adapted to be engaged by the fixed and loose 100 leaves of a hinge in the closed position of the corresponding side of the window, and means fixed to the stile and adapted to flexibly engage the loose leaf to retain it in same position relative to the fixed leaf when the 105 sash is in open and in closed position.

6. In an either-way casement window, the combination with a hinge on each stile, one leaf of each hinge being fixed to the stile and the other leaf being loose, of a locking 110 part on the loose leaf, a locking device carried by the window frame adapted to engage the said locking part on the loose leaf, a handle for operating the said locking device, and an automatic catch device on the 115 window frame adapted to prevent the handle from being turned into the locking position while the corresponding side of the window is open.

In testimony whereof I have signed my 120 name to this specification.

EDMUND GEORGE BAXTER.
